ATTORNEYS

UNITED STATES PATENT OFFICE.

MAX R. LEHMAN, OF QUINCY, ILLINOIS.

DESIGN FOR A STOVE.

51,345.

Specification for Design.

Patented Oct. 9, 1917.

Application filed August 23, 1917. Serial No. 187,891. Term of patent 7 years.

To all whom it may concern:

Be it known that I, MAX R. LEHMAN, a citizen of the United States, and a resident of the city of Quincy, county of Adams, State of Illinois, have invented a new, original, and ornamental Design for a Stove, of which the following is a specification, reference being had to the accompanying drawing, forming part thereof.

The drawing is a front elevation of the stove illustrating my new design.

I claim:

The ornamental design for a stove substantially as shown.

MAX R. LEHMAN.

Witnesses:

ALOIS C. HECKLE,
JACOB R. WIBLE.
